UNITED STATES PATENT OFFICE.

JOHN T. WILSON, OF JERSEY SHORE, PENNSYLVANIA.

PACKING FOR PISTONS AND PISTON-VALVES.

SPECIFICATION forming part of Letters Patent No. 759,582, dated May 10, 1904.

Application filed August 10, 1903. Serial No. 168,942. (No model.)

To all whom it may concern:

Be it known that I, JOHN T. WILSON, a citizen of the United States, residing at Jersey Shore, in the county of Lycoming and State of Pennsylvania, have invented new and useful Improvements in Packing for Pistons and Piston-Valves, of which the following is a specification.

The object of my invention is the production of a piston-packing for piston-valves and pistons which shall have rings so constructed and arranged that when the engine is working steam or other fluid motive power the position of the packing-ring relative to the bushing or inner surface of the cylinder will remain substantially unchanged throughout the entire stroke of the piston-valve or piston and the degree of frictional pressure of the outer or circumferential surface of the ring against the inner surface of a bushing or cylinder be substantially constant; which shall have the rings so constructed and arranged that when the engine is working steam the packing ring or rings will be rendered substantially solid or rigid; which shall have the rings so constructed and arranged that steam or other motive fluid can come in contact with the inner surface of the packing-ring and force it outwardly against a bushing or the inner surface of a cylinder and not cause excessive friction; which shall have the rings so constructed and arranged that when the engine is not working steam the packing-ring will automatically adjust itself to the inner surface of the bushing or cylinder, and thus compensate for wear, and which, finally, shall have the rings so constructed and arranged that they will be durable and efficient, obviate the necessity of special adjustment by hand, and, withal, possess many other desirable features and characteristics constituting the packing a superior means for performing the requisite functions.

With the above ends in view my invention consists in a packing embracing a packing-ring, a wedge-ring, and a clamping-ring relatively so disposed that when motive fluid is admitted to the engine it will pass to the inner surfaces of the rings and will act upon the wedge-ring and packing-ring and change their

diameters and by pressure render the packing-ring substantially rigid or solid.

It further consists in a packing comprising a packing-ring, a clamping-ring, and a wedge-ring, motive fluid being admitted to all the rings.

Finally, it consists in certain novelties of construction and combinations and arrangements of parts hereinafter set forth and claimed.

The accompanying drawings illustrate four pictured examples of the physical embodiment of my invention, which are constructed and arranged according to the best of the several modes I have so far devised for the application of the principle.

Figure 1 illustrates in section a piston or piston-valve, showing two sets of packing-rings. Fig. 2 illustrates a half-section of an engine-piston with two sets of packing-rings and means for introducing fluid motive power to each of said sets of rings from either side of the piston. Fig. 3 illustrates a half-section of a piston-valve provided with a wide packing-ring, a clamping-ring, and a relatively wide wedge-ring and means for allowing motive fluid to pass to the inner surfaces of the rings. Fig. 4 shows a modified construction of a piston-valve having two sets of packings and a ring interposed between them, also means for allowing motive fluid to pass to the inner surfaces of both sets of rings.

Referring to the several figures, the numeral 1 designates the body of a piston or a piston-valve, which may be of any suitable construction; 2, removable rings secured to the body of the piston or piston-valve by bolts or otherwise; 3, bolts holding the rings to the body of the piston or piston-valve; 4, recesses formed within the circumference of a piston or piston-valve, which recesses are adapted to receive and hold the packing; 5, a packing-ring; 6, a clamping or wall ring; 7, a wedge-ring, and 8 passages for steam to the under surfaces of the rings.

In Fig. 2 the numeral 9 designates a movable valve which is located in a passage 10, enlarged at the center to hold the valve in position, the said valve having beveled ends to

fit beveled seats, as shown. When steam is admitted to one side of the piston, the valve is shifted longitudinally and closes the opening to the opposite side of the piston, and at 5 the same time live motive fluid may pass by passage 11 to the under sides of both sets of packing-rings.

In Fig. 4 the numeral 12 designates a removable ring secured to the end of the piston- 10 spool and by the removal of which all of the rings can be shifted from the end of the spool, and 13 is a ring located between the two sets of packing-rings and which closely fits the circumference of the end of the spool.

15 In the several examples I have illustrated by cross-lines the lap-joints of the packing-rings and wedge-rings, and inasmuch as the joints may be of any suitable construction well known in the art I have not illustrated 20 them in detail. In all cases the clamping or wall ring is integral and cannot appreciably expand, whereas the packing-rings and wedge-rings may all expand under the pressure of fluid motive power and contract by their own 25 resiliency when motive fluid is shut off.

It will be observed that in all the examples motive fluid is admitted to the under surface of the packing-ring and the wedge-ring, that motive fluid when admitted acts upon the 30 wedge-ring and packing-ring and changes the diameters, that the clamping-ring cannot appreciably change its diameter, but forces the packing-ring against the wall of the piston or piston-valve, which wall constitutes one of the 35 boundaries of each recess, and that when motive fluid is shut off the packing-ring may automatically by its own resiliency adjust itself to the inner surface of the cylinder or bushing.

While I have illustrated and described only 40 four examples of the physical embodiment of my invention and in connection with piston-valves and pistons, I do not thereby intend to limit its scope to such specific examples, inasmuch as the principle can be embodied 45 by other modes and in a multiplicity of forms and combinations. The form or shape and dimensions and arrangements of the several rings may be changed and, as before stated, any style of joint-plate or lap-joint be selected 50 to form a closed joint, as they are not of the essence of my invention. Other modifications, as well as additions or omissions of parts or elements, I shall not regard as substantial departures provided those used are 55 for securing the desired mode of operation.

What I claim as new, and desire to secure by Letters Patent, is—

1. The combination with a piston or piston-

valve, of a packing-ring, an integral clamp- 60 ing-ring, and a wedge-ring, there being a pas- sage for steam to the under surface of all the rings.

2. The combination with a piston or piston- 65 valve, of a packing-ring, a non-expansible clamping-ring, and a wedge-ring; said rings being arranged in parallel planes and the non- 70 expansible clamping-ring being interposed between the packing-ring and the wedge-ring, and means for introducing motive fluid to the under surfaces of the packing and wedge 75 rings.

3. The combination with a piston or piston- 80 valve, of a packing-ring, a clamping-ring, and a wedge-ring; and means for admitting motive fluid to the under surfaces of all the 85 rings.

4. The combination with a piston or piston- 90 valve, of a packing-ring, a beveled clamping- ring, and a wedge-ring, and means for admitting motive fluid to the under surfaces of all the 95 rings.

5. The combination with a piston or piston- 100 valve, of an expansible packing-ring, a non- 105 expansible clamping-ring, and an expansible wedge-ring which bears against the clamping-ring; said packing-ring having a beveled surface which is in frictional contact with a beveled surface of the clamping-ring, and means for admitting motive fluid to the under surfaces of the rings.

6. The combination with a piston or piston- 110 valve, of a packing-ring, a wedge-ring, and a clamping-ring, said rings being located in parallel planes within a groove and said piston or piston-valve provided with a motive-fluid- 115 admission passage to the three rings from each side of the piston or piston-valve.

7. The combination with a piston or piston- 120 valve, of two sets of packing-rings each com- 125 prising an expansible packing-ring, an ex- 130 pansible wedge-ring, and a non-expansible clamping-ring, a passage to the under sur- 135 faces of each set of rings from each side of the piston or piston-valve, and means consist- 140 ing of a movable valve which prevents the 145 discharge of motive fluid to the opposite side of the piston or piston-valve when it is ad- 150 mitted from one of the sides to the under sur- 155 faces of the packings.

In testimony whereof I affix my signature in 160 presence of two witnesses.

JOHN T. WILSON.
